LAMP PACKAGE

Robert M. Hurley, Lexington, Mass., assignor to Sylvania
Electric Products Inc., a corporation of Delaware

Filed July 3, 1967, Ser. No. 7,675

Term of patent 14 years

(Cl. D9—224)

FIG. 1

The dominant features of my design reside in the portion shown in full lines.

I claim:

The ornamental design for a lamp package, as shown and described.
